UNITED STATES PATENT OFFICE

143,314

DESIGN FOR A TOOTHBRUSH HOLDER

Fred E. Hart, deceased, late of South Gate, Calif.,
by Ruth L. Hart, executrix, South Gate, Calif.

Application February 17, 1945, Serial No. 118,006

Term of patent 14 years

(Cl. D86—10)

To all whom it may concern:

Be it known that Fred E. Hart, deceased, who resided at South Gate, in the county of Los Angeles and State of California, has invented a new, original, and ornamental Design for Toothbrush Holders, of which the following is a specification, reference being had to the accompanying drawing, forming part thereof.

Fig. 1 is a view in elevation of the side of a toothbrush holder showing the new design;

Fig. 2 is a top plan view thereof;

Fig. 3 is a bottom plan view thereof;

Fig. 4 is a view taken from the left of Fig. 1 with the cap in raised position;

Fig. 5 is a top plan view of the holder with the cap removed; and

Fig. 6 is a bottom plan view of the cap shown in Figs. 1, 2 and 4.

What is claimed is:

The ornamental design for a toothbrush holder, as shown.

RUTH L. HART.

Executrix of the Estate of Fred E. Hart, Deceased.
